UNITED STATES PATENT OFFICE

2,511,715

MULTIPLE TRAY SUPPORTING RACK

John Kappel, Chicago, Ill.

Application October 31, 1945, Serial No. 625,793

1 Claim. (Cl. 211—163)

1

My invention relates to improvements in tray supporting racks and similar devices.

My invention relates more particularly to improvements in the type of tray supporting racks used in bakeries, kitchens of large hotels and other places where a considerable quantity of pan rolls, doughnuts, buns and other similar types of bakery goods are handled.

The principal object of the present invention is to provide an improved supporting rack of the type described which possesses many advantages over those heretofore produced including greater loading capacity, ease of accessibility and ease of movement.

A further object is to provide an improved tray rack that will have a plurality of rows of shelves extending outwardly radially from a common axis, supported in such manner that the entire unit may be moved in a circular direction by grasping any shelf and swinging the entire unit about its pivot.

A further object of the invention is to provide a revolving tray rack of the type described that is extremely sturdy and rigid, yet sufficiently light so that any ordinary person is able to move the same about at will.

A further object of the invention is to provide a revolving tray rack construction of the type described that can be easily and cheaply built and will not easily become broken or out of order even when subjected to long and hard usage.

Other objects and advantages will be more apparent from the following description wherein reference is had to the accompanying three sheets of drawings, upon which:

Fig. 1 is a longitudinal cross-sectional view through the preferred form of my improved revolving tray rack;

Fig. 1a is a fragmentary cross-sectional view showing the manner in which a supporting hook is fastened through the entire unit;

Fig. 2 is a plan-sectional view of my improved revolving tray rack taken generally on the lines 2—2 of Fig. 1;

Fig. 3 is a side elevational view of a modified form of the invention in which only two rows of racks are illustrated;

Fig. 4 is a plan sectional view thereof taken generally on the line 4—4 of Fig. 3; and

Fig. 4a is an enlarged fragmentary sectional view of the upper part of the tray rack showing the hook and the manner in which the same is connected to the tray rack.

In the preferred embodiment of the invention which I have chosen to illustrate, in Fig. 1, I have

2

shown the base 12 which has a combined thrust and radial bearing 14 provided axial thereof to support a vertically disposed post member 16. The post member 16 may be provided with collars 18 and 20 at its lower and upper ends respectively. Radially directed angle members 22 extend outwardly from the lower collar 18 and similar radially extended angle members 24 extend outwardly from the upper collar 20. The lower angle members 22 are welded or otherwise secured to an octagonally shaped frame member 26 which is formed of angle iron rigidly secured in the octagonal shape shown. The upper angle members 24 are similarly connected to an octagonally shaped frame member 28 adjacent the upper end of the tray rack. The octagonal frames 26 and 28 are then suitably connected by corner angle members 30 which are welded to both the upper and the lower frame to provide a rigid and integral structure.

As thus far described, I have provided a base and a rotatable octagonal frame which is mounted thereon and capable of rotation upon the combined radial and thrust bearing 14.

In order, however, to support this frame even unevenly loaded, as will be later explained, I have provided a plurality of roller members 32 which are universally mounted and fastened to the lower side of the frame 26 so that a portion of the load of the frame and the trays which is supported will be carried adjacent the sides of the octagon.

Tray racks 36, all similar in construction, may be formed of rod bent to a U-shape and fastened to facing legs of the angle upright members 30 spaced a distance of approximately six inches apart. Each of the legs may have a longitudinal brace 38 and a cross-brace 40 so that larger or smaller trays may be placed upon the same. The inner ends of the rods may be welded or otherwise secured to the upright legs of the angles 40.

I provide alternate rows of tray racks 42 which are spaced approximately six inches apart and between the rows of racks 36. The racks 42 are similar in construction to the racks 36 and may have the inner ends thereof welded or otherwise secured to upright support members 44 which are secured at both their upper and lower ends to the frame members 26 and 28 by the strap members 48 and 50. The tray racks 42 may also be braced with a radial brace 52 and a cross-brace 54 and be welded or otherwise rigidly secured at their inner ends to the upright angles 44 hereinbefore described.

With the construction thus described, it can be seen that I have provided a rotatable multiple tray support which provides in the normal height which is practical approximately 20 rows of racks, eight to the row, or 160 racks. And this in a space which is comparatively compact so that anyone of the racks is easily accessible and which has the further advantage of being capable of rotation, so that a person may stand in one position and, by merely swinging the unit about its pivot, place trays or remove trays from any of the other rows of racks desired.

Multiple trays racks of the type described are sometimes inserted into ovens loaded with trays of goods to be baked, and frequently the means for supporting the same in the oven may consist of an overhead trolley arrangement. Accordingly, in Fig. 1a, I have shown a hook member 51 which is rotatably fastened by a nut 53 to the flange 20 to which the upper end of the post member 16 has been connected. With this construction, the entire unit can be lifted bodily, the base 12 being rotatable upon the post 16, but being carried thereby.

In the modified form of the invention which I have shown in Figs. 3 and 4, I have provided a base which includes the four legs 60 that extend outwardly from a central pivot 62. Each of the legs are provided with roller casters 64 universally mounted so that the unit may be moved in any desired direction. Upon the pivot 62 which may include a combined roller and thrust bearing 66, I have mounted a center post 68 which may carry a pair of horizontal wooden frame members 70 and 72. These frame members extend sideways and connect to vertical post members 74 and 76. As thus far described, the multiple base 60 may support a rotatable frame which includes the center post 68 mounted in the bearing 66 and which carries the rectangular frame consisting of the upper and lower cross-members 70 and 72 and the vertical frame members 74 and 76.

The vertical frame members 74 and 76 may have a plurality of tray racks 78 and 80 secured thereto extending in opposite directions from the sides thereof. Each of the tray racks may include a bracing structure having a longitudinal brace 82 and a cross-brace 84. Certain of the tray racks 78a and 80a are extended a short distance further than the rest so that these may be grasped to swing the complete unit about on its pivot.

For a comparatively high revolving tray rack of this type it is sometimes desirable to provide additional bracing to prevent it from becoming top-heavy, and accordingly I have shown a pair of angle members 90 and 92 which extend outwardly from the lower end of the post 68 and downwardly as shown at 94 and 96. The lower ends of these members are provided with a universally mounted roller caster 98. With this construction it will be comparatively easy to move the entire unit about, and any danger of the

same tipping over due to top-heaviness is thus overcome.

The tray rack which I have shown in Figs. 3 and 4 may also be provided with means for carrying the same upon an overhead track or support if desired. Accordingly, in Fig. 4a, I have shown a hook member 73 which has a reduced portion 75 extending through an opening 77 in the collar 79 secured to the upper end of the post 68 and also to the cross-brace 72. A nut member 81 holds the hook in place, but permits rotation of the entire unit upon the hook when the hook is supported by an overhead track or similar support.

15 While I have shown and described the preferred embodiment and one modification of the invention, it will be understood by those skilled in the art that changes and modifications may be made in the exact details shown, and I do not 20 wish to be limited in any particular; rather what I desire to secure and protect by Letters Patent of the United States is:

25 A revolvable tray rack construction including a supporting base, a vertical post member rotatably positioned thereon, said post having collars at its upper and lower ends respectively, radially directed angle members extending outwardly from said collars, polygonally shaped frames secured to said top and bottom angle members, 30 upright braces connecting said frames at their corners and medially of each side, tray supporting racks secured to each pair of adjacent corner braces and a row of tray supporting racks secured to each pair of adjacent medial upright braces.

35 JOHN KAPPEL.
